COMBINED WALLET, PURSE, AND FACIAL TISSUE HOLDER

Herbert S. Chase, New York, N. Y.

Application December 31, 1949, Serial No. 6,951

Term of patent 7 years

(Cl. D87—3)

To all whom it may concern:

Be it known that I, Herbert S. Chase, a citizen of the United States of America, residing in New York city, county of New York, and State of New York, have invented a new, original, and ornamental Design for a Combined Wallet, Purse, and Facial Tissue Holder, of which the following is a specification, reference being had to the accompanying drawing, forming part thereof, wherein,

Figure 1 is a front elevational view of a combined wallet, purse, and facial tissue holder, showing my new design in closed position.

I claim:

The ornamental design for a combined wallet, purse, and facial tissue holder, substantially as shown.

HERBERT S. CHASE.
